CLAIM

The ornamental design for a clip-on, clip-in thermal unit for temperature modification of a foodstuff in a container, as shown and described.

DESCRIPTION

FIG. 1 is a perspective view of the first embodiment of the clip-on, clip-in thermal unit for temperature modification of a foodstuff in a container, showing our new design;

FIG. 2 is a front elevation of the thermal unit shown in FIG. 1, with the clip thereof in the rearmost position; FIG. 3 is a side elevation of the thermal unit shown in FIG. 2 with the clip thereof positioned at the right side; FIG. 4 is a top plan view of the thermal unit shown in FIG. 1;

FIG. 5 is a bottom plan view of the thermal unit shown in FIG. 1;

FIG. 6 is a perspective view of a second embodiment of the thermal unit of the invention, wherein the rearmost face is similar to the unobstructed front view face;

FIG. 7 is a perspective view of a third embodiment of the thermal unit of the invention, wherein the rear two faces are similar to the unobstructed front view face; and,

FIG. 8 is a perspective view of a fourth embodiment of the thermal unit of the invention, wherein the hidden rear cylindrical portion of the unit is similar to the unobstructed front cylindrical portion thereof.

FIG. 1

FIG. 2

FIG. 3

FIG. 4

FIG. 5

FIG. 6

FIG. 7

FIG. 8
